UNITED STATES PATENT OFFICE.

OLMEDO CORTEZ WYSONG, OF GREENSBORO, NORTH CAROLINA.

ABRASIVE APPARATUS.

No. 832,889.

Specification of Letters Patent.

Patented Oct. 9, 1906.

Application filed December 15, 1905. Serial No. 291,836.

To all whom it may concern:

Be it known that I, OLMEDO CORTEZ WYSONG, a citizen of the United States, residing at Greensboro, in the county of Guilford and 5 State of North Carolina, have invented certain new and useful Improvements in Abrasive Apparatus, of which the following is a specification.

My invention relates to improvements in 10 woodworking-machines. One of its objects is to provide an abrasive band-carrying mechanism adapted to be conveniently adjusted so that the band will run in either a horizontal or vertical plane.

Another object is to provide in connection therewith means for supporting the band opposite the point where the work is applied.

Another object is to provide improved means for supporting and counterbalancing 20 the adjustable frame.

It further consists in certain details of form, combination, and arrangement, all of which will be more fully set forth in the description of the accompanying drawings, in 25 which—

Figure 1 is a side elevation of my improved mechanism in position for the band to travel in a horizontal plane. Fig. 2 is a top plan view of the same. Fig. 3 is an end view of 30 the mechanism in same position as in Fig. 1. Fig. 4 is an end view in position for the band to travel in a vertical plane.

A represents the base, in which is journaled a sleeve B.

C represents the adjustable frame attached to the sleeve B, which serves as a journal to the same, and also journaled, by means of an ear c and pin c', to the upright A' of the frame A. A spring-actuated latch a serves 40 by entering one or other of a series of holes in the flange b of sleeve B to lock the frame to any adjustable position.

D D' represent counterweights which enable the frame C to be conveniently moved 45 to any desired position.

E represents the main driving-shaft, which receives motion by means of a belt on pulley F. The shaft E is journaled in boxes e e', box e being attached indirectly to frame C 50 through the counterweight D and box e' formed integral with sleeve B, through the center of which shaft E passes.

The shaft G is mounted at right angles to shaft E in boxes g g' and is driven from shaft 55 E by means of beveled gears H I, which may be either toothed or friction gears. Shaft G

also carries a pulley J, which serves as a driving-pulley for the abrasive belt K.

L represents a pulley mounted upon a stud-shaft l, carried by an adjustable plate M at 60 the opposite end of frame C, and over which the opposite end of the belt passes. The plate M is pivoted at m to a plate m', which slides on ways on the frame C and may be adjusted to or from pulley J by means of a 65 screw N. Plate M may also be adjusted relative to plate m' to align pulley L by means of screws n n', engaging an ear h on plate M, after which the parts are locked in position by bolt h'. 70

Frame C is provided with slots O, by means of which a work support or table P and one or more belt supports or forms R may be attached to the frame and adjusted to any desired position. As shown, table P is provided with a slotted shank p, by means of which it is clamped by bolt p' to frame C and may be adjusted along the frame and to varying distances therefrom or detached, if desired. The form R, which will vary with the 80 character of the work to be finished, is shown supported upon a slotted shank R', similar to that supporting table P. A stud-shaft r is pivoted by bolt r' to the shank R', so as to be adjusted to varying angles relative thereto. 85

S represents a sleeve adjustable vertically and circumferentially on shaft r and locked thereto by set-screw S'.

T represents the form-holder pivoted to sleeve S and locked to its adjusted position 90 relative thereto by set-screw t.

The form R, which is interchangeable in the holder with the other forms, may be plain or shaped to a counterpart of the work to be treated and is preferably provided with a 95 smooth-faced cushion. The form may thus be adjusted to any desired position relative to the belt and frame C. The rear face of the abrasive belt is drawn across the face of the form and the work pressed against the belt 100 opposite the form, which if the work is of irregular outline causes the belt to conform to the outline of the work.

As indicated in Figs. 3 and 4, upon releasing the latch a the frame C may be turned to 105 any desired angle relative to the base A, according to the requirements of the work or convenience of the operator. By journaling the frame by means of sleeve B to the base and mounting the driving-shaft within the 110 sleeve the driving-shaft is relieved of any strain due to the weight of frame C and

parts carried thereby. By journaling the frame at opposite ends to the base the frame may be made lighter in weight and subject to less vibration, and by counterweighting the frame at opposite ends any torsional strain on the frame is avoided.

The mechanism herein shown is capable of considerable modification without departing from the principle of my invention.

10 Having described my invention, what I claim is—

1. In a mechanism of the character indicated, a frame carrying a plurality of pulleys adapted to support an abrasive band, said frame being journaled upon a horizontal axis and adjustable thereon so as to bring the axes of the band-supporting pulleys into either a horizontal or vertical position, and means for driving one of said band-supporting pulleys in whatever position it may be adjusted.
2. In a mechanism of the character indicated, a base, a frame carrying a plurality of pulleys adapted to support an abrasive belt, said frame being journaled to opposite ends 25 of said base upon a horizontal axis and adjustable thereon so as to permit the axes of the abrasive-belt-supporting pulleys to be adjusted into either a vertical or a horizontal position, and mechanism for driving one of 30 said belt-supporting pulleys.
3. In a mechanism of the character indicated, a frame carrying a plurality of pulleys, an abrasive band carried by said pulleys, means for adjusting said frame so that the 35 axes of said pulleys will assume either a vertical or a horizontal position, and mechanism for driving one of said pulleys in whatever position said frame may be adjusted.
4. In a mechanism of the character indicated, a base, a frame carrying a plurality of pulleys and journaled upon a horizontal axis to said base, and adjustable thereon so as to permit the axes of said pulleys to assume either a vertical or horizontal position, an 45 abrasive belt supported upon said pulleys, means for driving one of said pulleys to drive said abrasive belt, and a form carried by said frame adapted to support the rear face of the belt at the point where the work is applied.
5. In a mechanism of the character indicated, a base, a frame carrying a plurality of pulleys and journaled upon a horizontal axis to said base and adjustable thereon so as to permit the axes of said pulleys to assume

either a vertical or horizontal position, an 55 abrasive belt supported upon said pulleys, a driving-shaft journaled in fixed relations to said base, means for transmitting motion from said driving-shaft to one of said pulleys carried by said frame to drive the abrasive 60 belt, and a form carried by said frame adapted to support the rear face of the abrasive belt at the point where the work is applied.

6. In a mechanism of the character indicated, a base, a frame journaled thereto at 65 opposite ends and adapted to be adjusted to positions varying from a horizontal to a vertical plane relative to said base, an abrasive belt, a plurality of pulleys carried by said frame adapted to support said abrasive belt, 70 and means for driving one of said pulleys to drive the belt.

7. In a mechanism of the character indicated, a base, a counterweighted frame journaled thereto and adapted to be adjusted 75 into either a horizontal or a vertical plane relative to said base an abrasive belt, a plurality of pulleys carried by said frame and adapted to support said abrasive belt, a form carried by said frame adapted to support the rear 80 face of said abrasive belt, and means for driving one of said pulleys to drive said abrasive belt.

8. In a mechanism of the character indicated, a base, a frame journaled thereto at 85 opposite ends and adapted to be adjusted to varying positions relative to said base, counterweights carried at opposite ends of said frame, an abrasive belt, a plurality of pulleys carried by said frame adapted to support said 90 abrasive belt, and means for driving one of said pulleys to drive the belt.

9. In a mechanism of the character indicated, a base, a frame journaled thereto and adapted to be adjusted into either a horizontal 95 or vertical plane relative to said base, a counterweight carried by said frame, mechanism for locking the frame to its adjusted position, an abrasive belt, a plurality of pulleys carried by said frame adapted to support 100 said abrasive belt, and means for driving one of said pulleys to drive said belt.

In testimony whereof I have affixed my signature in presence of two witnesses.

OLMEDO CORTEZ WYSONG.
